UNITED STATES PATENT OFFICE

149,639

DESIGN FOR A COMBINED FLAG AND STAFF
THEREFOR

Marie Louise Helehan, Portland, Oreg.

Application May 24, 1946, Serial No. 130,047

Term of patent 14 years

(Cl. D29—17)

To all whom it may concern:

Be it known that I, Marie L. Helehan, a citizen of the United States, residing at Portland, in the county of Multnomah and State of Oregon, have invented a new, original, and ornamental Design for a Combined Flag and Staff Therefor, of which the following is a specification, reference being had to the accompanying drawing, forming a part thereof.

The figure is a front view of a combined flag and staff therefor, showing my new design.

I claim:

The ornamental design for a combined flag and staff therefor, as shown.

MARIE LOUISE HELEHAN.
